Primary Examiner — Wendy L Arminio*Assistant Examiner* — Maheen Khurshid(74) *Attorney, Agent, or Firm* — Sterne, Kessler, Goldstein & Fox P.L.L.C.; Charles B. Cappellari(57) **CLAIM**

The ornamental design for a cap for closing a vial, as shown and described.

DESCRIPTION

FIG. 1 is a top front perspective view of a cap for closing a vial showing the claimed design;

FIG. 2 is a bottom front perspective view thereof; and,
FIG. 3 is a front view thereof.

Portions of the cap for closing a vial that are not shown form no part of the claimed design.

The broken lines in the figures show portions of the cap for closing a vial that form no part of the claimed design.

1 Claim, 2 Drawing Sheets(56)
